UNITED STATES PATENT OFFICE

2,491,554

TRAY

Alan W. Finley, McKees Rocks, Pa.

Application October 1, 1946, Serial No. 700,517

3 Claims. (Cl. 229—30)

1

My invention relates to an advertising table piece.

An important object of the invention is to provide a table piece which will keep the manufactured product before the customer, and which is usable and practical.

A further object of the invention is to provide a device of the above-mentioned character which is formed from a blank which may be die cut, and printed in one operation.

A further object of the invention is to provide a device of the above-mentioned character which will afford an ash tray, attached matches, and advertising space.

Other objects and advantages of the invention will be apparent during the course of the following description:

In the accompanying drawings forming a part of this application, and in which like numerals are employed to designate like parts throughout the same,

Figure 1 is a side elevation of the advertising table piece embodying my invention,

Figure 2 is a similar view at right angles to Figure 1,

Figure 3 is a plan view of the blank from which the device is formed,

Figure 3a is a section on line 3a—3a of Figure 2,

Figure 4 is a side elevation of a slightly modified form of advertising table piece,

Figure 5 is a similar view at right angles to Figure 4, and

Figure 6 is a fragmentary plan view of the blank.

In the drawings, wherein for the purpose of illustration are shown preferred embodiments of my invention, attention being called first to Figures 1 to 3 inclusive, the numeral 10 designates a blank which is formed from a sheet which is suitably stiff and foldable. This sheet may be formed from any material which will meet the fire underwriters' requirements. The blank is stamped to provide a pair of blanks 11, each shaped to represent an article of manufacture like an open-necked bottle. At the meeting ends of the blanks 11, the blank is scored transversely to provide a crease line, as shown at 12. Each blank has a multi-sided section 13 secured at one end and each blank 11 is connected to each section 13 by a crease line 14. Each multisided section has a strip 20 extending along its other end and also has a strip 18 extending longitudinally along each of its sides. The strips 18

2

are connected to each section 13 by crease lines 15 and 16, as shown in Figure 3.

In assembling the device, the strips 18 and 20 are folded along the respective crease lines 15 and 16, and form upstanding side walls and an end wall of an ash tray. As shown in Figure 3, an end 19 of each of the longitudinally-extending strips 18 projects beyond the crease lines 14. Each of the projecting ends 19 of one of the sections 13, right-hand section of Figure 3, is provided with an inwardly-extending tongue 24, while each of the projecting ends 19 of the other of said sections 13, left-hand section of Figure 3, has an outwardly-extending tongue 23. The tongues 23 and 24 are each formed by cutting a pair of spaced slits 25 transversely of the projecting ends 19 of the strips 18.

When the blanks 11 are folded upon each other and the tongues on the projecting ends 19 of one of the sections 13 interengage the tongues 24 on the projecting ends of the other section 13, the sections form a tray for the reception of ashes therein.

The multi-sided sections 13 provide spaces A for advertisements, and the blanks 11 provide spaces B for advertisements.

Book matches 26 are arranged upon the outer faces of the blanks 11, and may be secured thereto by any suitable means.

It is thus seen that I have provided an advertising table piece embodying an ash tray having upstanding sides and a vertical member including the blanks 11, representing a manufactured product, such as a bottle. When the strips 18 are substantially vertical, the ends 19 of the strips 18 to the left, Figure 3, are arranged inwardly of the strips 18, to the right and the upstanding tongues 22 are disposed upon the outer faces of the strips 18 to the right, Figure 3, while the depending tongues 24 are disposed upon the inner faces of the strips 18 to the left.

In Figures 4, 5 and 6, I have shown a slight modified form of the invention. The inner ends of the blanks 11 are connected by a tab 27, foldable upon crease lines 28. The tab 27 has a slot 29 for the passage of matches. As shown in Figure 5, the tab 27 is horizontally arranged, and the upper ends of the blanks 11 diverge upwardly, to form a space for receiving a book 30 of pull matches, held in place by any suitable means. The matches may be withdrawn by an upward movement. All other parts of the device remain identical with those shown and described in connection with the first form of my invention.

The invention is not restricted to the sections

11 representing a bottle, as they may be made in shapes to represent any other desired manufactured product.

It is to be understood that the form of my invention herewith shown and described is to be taken as a preferred example of same and that the various changes in the shape, size, and arrangement of parts may be resorted to without departing from the spirit of my invention or the scope of the subjoined claims.

Having thus described my invention, what I claim is:

1. An article of manufacture for use in producing an ash tray comprising a foldable structure, said structure comprising a pair of blanks interconnected with each other at one end by a crease line and foldable upon each other, each of said blanks being shaped to represent an article of manufacture, a multi-sided section having one end arranged adjacent to the other end of each of said blanks and interconnected with the latter by a crease line, each section having a strip extending along its other end and having a strip extending longitudinally along each of its sides, the respective strips being connected to each section by crease lines and foldable along said crease lines to form upstanding side walls and an end wall interconnected with the latter, one end of each of the longitudinally-extending strips projecting beyond the crease lines interconnecting the respective sections with said blanks, the projecting ends of the longitudinally-extending strips of one of said sections being each provided with a tongue extending inwardly and the projecting ends of the longitudinally-extending strips of the other of said sections being each provided with a tongue extending outwardly, the tongues on the projecting ends of one section interengaging the tongues on the projecting ends of the other section when said blanks are folded upon each other to thereby form a tray for the reception of ashes therein.

2. An article of manufacture for use in producing an ash tray comprising a foldable structure, said structure comprising a pair of blanks each shaped in the form of an open-necked bottle, the blanks being arranged so that the necks are in facing relation with respect to each other and interconnected by a crease line, a multi-sided section having one end arranged adjacent to the other end of each of said blanks and interconnected with the latter by a crease line, each section having a strip extending along its other end and having a strip extending longitudinally along each of its sides, the respective strips being connected to each section by crease lines and foldable along said crease lines to form upstanding

side walls and an end wall interconnected with the latter, one end of each of the longitudinally-extending strips projecting beyond the crease lines interconnecting the respective sections with said blanks, the projecting ends of the longitudinally-extending strips of one of said sections being each provided with a tongue extending inwardly and the projecting ends of the longitudinally-extending strips of the other of said sections being each provided with a tongue extending outwardly, the tongues on the projecting ends of one section interengaging the tongues on the projecting ends of the other section when said blanks are folded upon each other to thereby form a tray for the reception of ashes therein.

3. An article of manufacture for use in producing an ash tray comprising a foldable structure, said structure comprising a pair of blanks each shaped in the form of an open-necked bottle, the blanks being arranged so that the necks are in facing relation with respect to each other, a tab provided with a slot interposed between the facing necks and interconnected with said necks by crease lines, a multi-sided section having one end arranged adjacent to the other end of said bottle and interconnected with the latter by a crease line, each section having a strip extending along its other end and having a strip extending longitudinally along each of its sides, the respective strips being connected to each section by crease lines and foldable along said crease lines to form upstanding side walls and an end wall interconnected with the latter, one end of each of the longitudinally-extending strips projecting beyond the crease lines interconnecting the respective sections with said blanks, the projecting ends of the longitudinally-extending strips of one of said sections being each provided with a tongue extending inwardly and the projecting ends of the longitudinally-extending strips of the other of said sections being each provided with a tongue extending outwardly, the tongues on the projecting ends of one section interengaging the tongues on the projecting ends of the other section when said blanks are folded upon each other to thereby form a tray for the reception of ashes therein.
